US0D1025173S

(12) **United States Design Patent** (10) **Patent No.:** **US D1,025,173 S**
Au et al. (45) **Date of Patent:** **** Apr. 30, 2024**

(54) **MICROPHONE COVER OF A CAMERA HOUSING**

(71) Applicant: **GoPro, Inc.**, San Mateo, CA (US)

(72) Inventors: **Heman Au**, San Mateo, CA (US); **John George Muhlenkamp, IV**, Mapleton, UT (US); **Huy Phuong Nguyen**, Alpine, UT (US); **Zhijun Guo**, Shenzhen (CN)

(73) Assignee: **GoPro, Inc.**, San Mateo, CA (US)

(**) Term: **15 Years**

(21) Appl. No.: **29/849,211**

(22) Filed: **Aug. 9, 2022**

Related U.S. Application Data

(62) Division of application No. 29/829,243, filed on Mar. 3, 2022, now Pat. No. Des. 963,726, which is a division of application No. 29/746,616, filed on Aug. 14, 2020, now Pat. No. Des. 953,404.

CLAIM

The ornamental design for a microphone cover of a camera housing, as shown and described.

DESCRIPTION

FIG. 1 is a top, front and right side perspective view of a microphone cover of a camera housing showing our new design;

FIG. 2 is a top, rear and left side perspective view thereof; FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depict portions of the microphone cover of a camera housing that form no part of the claimed design.

1 Claim, 4 Drawing Sheets
